UNITED STATES PATENT OFFICE.

THADDEUS C. JOY, OF TITUSVILLE, PENNSYLVANIA, ASSIGNOR TO THADDEUS C. JOY AND DANIEL COLESTOCK.

DESIGN FOR A RADIATOR.

SPECIFICATION forming part of Design No. 20,583, dated March 17, 1891.

Application filed February 4, 1891. Serial No. 380,234. Term of patent 7 years.

To all whom it may concern:

Be it known that I, THADDEUS C. Joy, a citizen of the United States, residing at Titusville, in the county of Crawford and State of Pennsylvania, have invented and produced a new and original Design for Steam or Hot-Water Radiators; and I do hereby declare the following to be a full, clear, and exact description of the same, reference being had to the accompanying drawings, forming a part thereof.

My design relates to hollow fluted sections of steam or hot-water radiators; and the leading feature of the same consists in scallop-like ornamental depressions between the upper ends of the ribs of the radiator-sections formed in the crowning arch-shaped terminations of said sections, the said ornamental depressions forming an upward continuation of the flutes between the ribs of the sections from the base to or near the ridge of the crowning arch-shaped terminations of the sections, as illustrated in the accompanying drawings, in which—

Figure 1 is a side elevation of a radiator-section, showing my design; Fig. 2, an end view of two of the sections as placed side by side, showing my design; Fig. 3, a horizontal section of one of the radiator-sections; Fig. 4, a top view of a section, showing my design; and Fig. 5, a vertical section of a radiator-section, showing my design.

In the drawings, A designates the ribs, and B spaces between the ribs of the fluted columnar sections C; C', the beveled columnar ends of a radiator-section.

D is the crowning, beveled, and arched termination of the respective sections, the bevels thereof on each side extending from the ridge *a* of a section to the outer edges of

the ribs A, as shown in the drawings. A finishing-bead at the ridge *a* and extending up from the base of the section to and over the arching termination may be provided.

E are scallop-like ornamental depressions 45 formed in the beveled surfaces of the crowning arch-shaped terminations of the sections, the same extending from the bases to near the ridges of the arch terminations, as illustrated in the drawings.

This design gives a highly ornamental and symmetrical finish to the top portions of the respective fluted radiator-sections represented, and when such sections are set up so as to constitute a given-sized radiator a tasteful effect is produced, no top to give a finish being required.

Any tasteful or desirable ornamentation may be applied to the surface of the ornamenteally formed and scalloped crowning 6c arched terminations of the sections—such, for instance, as ornamental leaves or geometrical embellishing-figures; but while this is the case my design has special reference to the scallops in the crowning, arched, and 65 beveled terminations of the fluted sections, as represented in the drawings.

What I claim as my invention is—

The design for radiators, comprising sections having fluted side surfaces and the 70 crowning, arched, beveled, and scalloped terminations, as herein described, and shown in the accompanying drawings.

In testimony whereof I hereunto affix my signature in presence of two witnesses.

THADDEUS C. JOY.
